UNITED STATES PATENT OFFICE

2,501,019

ADJUSTABLE BOOK AND MAGAZINE
HOLDER

Purdy E. Attick, Chicago, Ill.

Application August 30, 1946, Serial No. 694,028

5 Claims. (Cl. 45—80)

1

This invention relates to an adjustable book and magazine holder, and more particularly, to a book and magazine holding device for holding the book or magazine in any position for the convenience of a reader, whether the reader is sitting upright or inclined, or whether lying in any of several positions.

A major object of this invention is to provide an improved book and magazine holder which is efficient, simple, practical in construction, and which will be of special benefit to handicapped persons by holding the book or magazine while permitting adjustment thereof to the proper angle and line of vision so that only one hand is required to turn pages and the reader will have the convenience of reading in any sitting or lying position.

Another object of this invention is to provide an improved book and magazine holder having a dual adjustment so that the book or magazine can be moved in a vertical plane to and adjusted forward position and then moved to the right or left and locked in finally adjusted position in which position there will be no interference to the turning of pages.

A further object of this invention is to provide an improved book and magazine holder for mechanically locking a book or magazine in position and in which hinge means are provided for varying the angle of inclination of the reading surface in a vertical plane, and in which additional means are provided for adjusting the reading surface to the right or the left while in said angle of inclination so that a book or magazine in the holder can be read by a reader in an upright sitting position, in an inclined sitting position, or from varying lying positions, including right and left sides, while maintaining the proper line and angle of vision.

Still another object of this invention is to provide a book and magazine holder for relieving the reader of the tiring and nerve upsetting strain of holding books, magazines, journals and the like and having adjustable means to at all times insure that the reading plane is at the proper angle to provide for correct vision so that the reader's hands may be at rest at all times except when turning a page which can be accomplished merely with one hand.

Still a further object of this invention is to provide a book and magazine holder for clamping a book and magazine in place and having means to hold the book and magazine at any open position and yet enabling a simple turning of pages and having means to hold each page

2

after it has been turned, and in which the entire holder with the reading matter attached in fixed position can be readily put aside and kept ready for instant resumption of reading at any later time.

It is still another object of this invention to provide a book or magazine holder having a book or magazine rest and clamping means for engaging the tops of the book or magazine covers, and in which extensible means are provided to accommodate books or magazines of varying height, and in which the book rest is provided with page guards for holding the pages as they are turned and which permit easy turning of pages.

It is still a further object of this invention to provide a book or magazine holder having a foldable upright which may be braced and locked in a number of angular positions, and having a rotatable carrier on the upright which may be rotated clockwise or counter-clockwise and locked in adjusted position.

Other objects and advantages of this invention will appear from the following specification and claims and from the accompanying drawing illustrating the invention, wherein:

Figure 1 is a side elevational view of the adjustable book and magazine holder of this invention;

Figure 2 is a front elevational view of the same;

Figure 3 is a rear elevational view of the same;

Figure 4 is a sectional view taken on line 4—4

of Fig. 1 and showing the construction of the book and magazine rest;

Figure 5 is a detail plan view showing one of the clamps for clamping the tops of the covers of the book or magazine;

Figure 6 is a detail front elevational view of the clamp shown in Fig. 5;

Figure 7 is a fragmentary front elevational view of the upright showing a modified locking means for the rotatable carrier; and

Figure 8 is a sectional detail view taken on line 8—8 of Fig. 7, and showing the modified locking means.

Referring to the drawing, reference numeral 1 refers to a base member and numeral 2 refers to an upright hinged to the base member 1 at 3. To the rear of the upright 2 is suitably secured a hinge plate 4 to which a brace or strut 5 is hinged at 6. A series of anchor sleeves 7 are suitably affixed to the base member 1, as clearly shown in Figure 1. The sleeves 7 may be attached singly to the base member 1 or may be mounted on or formed integrally with a plate 8 for attachment to the base member 1 in a series,

The ends 9 of the strut 5 are inturned, as shown by dotted lines in Figure 3, and the strut 5 is of such resiliency as to permit the ends 9 to be spread for insertion into the ends of the sleeves 7. Thus the strut or brace 5 may be affixed to any one of the sleeves 7 to adjust the inclination of the upright 2 from practically a vertical position to one of substantial backward incline.

A rotatable carrier 10 is pivotally mounted on a bolt 11, passing through carrier 10 and mounting same on the upright 2, as shown. A pin, eyelet, or other suitable means may be used in lieu of the bolt 11 within the scope of this invention. A rest, denoted generally by reference numeral 12, is fixed to the bottom of the rotatable carrier 10, and is composed of two pieces, a ledge 13 and a page guard 14. The ledge 13, as shown in Figure 1 is angular in cross-section and is suitably affixed to the bottom of the rotatable carrier 10. The vertical leg of the ledge 13 is provided with an opening 15 for receiving a bolt 16, passing through an arcuate slot 17 in upright 2, for a purpose to be described hereinafter. The horizontal leg 18 of ledge 13 is provided with an opening 19, receiving a bolt 20 which pivotally secures page guard 14 to the ledge 13. The page guard 14 is provided with upper and lower flanges 21 and 22, respectively, for receiving leg 18 therebetween, as clearly shown in Figure 1. The page guard 14 is provided with a pair of upwardly extending wing portions 23 which are adapted to press against the open pages of the book in a self-adjusting and equalizing manner due to the pivot at 20. The pivot 20 permits one wing member to be closer to the carrier 10 when the other wing member is farther from the carrier as when a book or magazine is open to a page near the beginning or near the end of the book or magazine. In use when a book is placed against carrier 10 on ledge 13, the wings 23 will bear against the open pages to retain them in position and yet due to the spacing and curvature of the wings 23, pages can be turned in a natural manner by lifting the bottom of a page from the wing 23 bearing thereagainst. After the page is turned, it can be easily positioned behind the other wing 23. Another opening 24 is provided through the page guard 14 and ledge 13 to permit movement of the pivot 20 to increase the distance of wings 23 from the carrier 10 when thick books are to be read.

An extensible plate 25 is mounted for slidable movement behind the rotatable carrier 10, the mounting consisting of a bolt 27 fixed in carrier 10 forming a guide for the slot 26 in extensible plate 25. Thus, plate 25 can be moved up or down, movement being limited only by the length of slot 26 to accommodate books and magazines of different heights.

At the top of extensible plate 25 are located a pair of adjustable clamps 28, shown in detail in Figures 5 and 6, adapted to clamp the front and back covers of the book or magazine against the carrier 10 or the plate 25. The clamps 28 each comprise a pair of integral spring-like ears mounted on a lever 29, both levers being pivoted on the same pin 30. The clamps are adapted to swing upwardly from the position shown in Figure 2 and when swung back to the Figure 2 position, the book cover may be held against the carrier 10 and plate 25 by the ears encompassing the top of the cover and the top portion of plate 25.

A guard 31 is provided as a fixed part of base 1 and is primarily for holding the bottom edge of

a newspaper, journal, or other matter too large to be locked into position on the carrier 10.

As indicated above, the rotatable carrier 10 is mounted on bolt 11 for swinging movement in a clockwise or counter-clockwise direction. This movement is limited to an arc of about 125°, i. e., limited by the movement of bolt 16 in arcuate slot 17. A knob or nut 32 is threaded onto bolt 16 so that the carrier 10 may be locked in adjusted arcuate position by tightening the knob 32 on bolt 16. The knob 32 also serves as a handle for swinging the carrier 10 to adjusted position. Thus, as the carrier 10 is rotated, the reading matter locked thereon will also be rotated to the adjusted desired position for best reading.

A modified form of locking means for the rotatable carrier is shown in Figures 7 and 8 wherein a series of holes 33 are provided at spaced intervals along an arcuate path in the upright 2'. The bottom of the carrier 10' is provided with a bolt 34 having a rounded tip 35 fitting into any one of the holes 33 in a spring-like manner. Thus, a mere turning of the carrier 10' will carry the bolt 34 into association with the proper hole 33 acting as a stop and holding member. This modification eliminates the screw knob 32.

When not in use, the book or magazine holder of this invention may be folded to a flat position by turning upright 2 against the base 1 after disconnecting the strut 5.

The dual-angular adjustment features of this device, about hinge 3 and about pivot 11, combine to provide a ready means of fixing the book or magazine into the proper fields of vision and light regardless of whether one is sitting upright in a chair or bed, in a semi-reclining position, or is lying on the back or on either side. The base 1, if desired, can be rested on the chest of a reader lying on the back, or on the bed itself on either side, thus relieving the hands and arms of all strain.

The holder with a book or magazine locked in place on the carrier may be readily folded into a flat position without disturbance to any right or left adjustment made on page upon which reading is to be later resumed by merely releasing the strut 5 and turning upright 2 against base 1.

While certain specific embodiments of this invention have been shown, it will be understood that various modifications may be made within the spirit of the invention. Therefore, no limitations on the invention are intended other than are imposed by the scope of the appended claims.

What is claimed is :

1. A book and magazine holder comprising a base, an upright hinged to said base for angular movement to and from said base, means for locking said upright in adjusted angular position, a carrier rotatably mounted on said upright, a book rest at the bottom of said carrier, a page guard, said page guard including at least one substantially horizontally-disposed flange and a pair of integrally connected and substantially vertically-extending wings for retaining right and left pages of an open book in position, substantially vertically-extending pivot means pivotally connecting said horizontal flange of said page guard to said rest, said page guard being constructed and arranged to swing about its pivot automatically to adapt said wings to bear against opposite pages of an open book irrespective of the point at which the book is open.
2. A book and magazine holder comprising a base, an upright hinged to said base for angular

movement to and from said base, a carrier rotatably mounted on said upright, a book rest at the bottom of said carrier, a page guard mounted on said rest for holding the pages of an open book on said rest, a vertically extensible plate mounted on said carrier, a pin and slot connection limiting movement of said extensible plate, and clamps at the upper end of said extensible plate adapted to clamp the front and back covers of a book on said rest, means pivotally connecting said clamps to said plate for pivotal movement in a plane parallel to the plane of said plate to and from cover-clamping and cover-releasing positions, said extensible plate being movable to any extended position for accommodation of books of different heights.

3. A book and magazine holder comprising a base, an upright hinged to said base for angular movement relative thereto, a carrier rotatably mounted on said upright for clockwise or counter-clockwise movement relative thereto in a plane parallel to the plane of said upright, an arcuate series of spaced detents formed in said upright equidistant from the center of rotation of said carrier, and a round ended bolt mounted in said carrier for selective locking engagement with any one of said detents to hold said carrier in adjusted position, said bolt and detents being constructed and arranged to be sprung into or out of engagement upon manual rotation of said carrier.

4. In a book and magazine holder, including a carrier adapted to support an open book in a reading position, the improvement comprising means for clamping book covers to said carrier, comprising a pair of clamps, means mounting said clamps on said carrier for adjustment vertically thereof to accommodate books of different

heights, and means pivotally connecting said clamps to said last-named means for pivotal movement in a plane parallel to the plane of said carrier to and from cover-clamping and cover-releasing positions.

5. A book and magazine holder, comprising a base, an upright hinged to said base for angular movement relative thereto, a carrier rotatably mounted on said upright for clockwise or counter-clockwise movement relative thereto in a plane parallel to the plane of said upright, one of said upright and carrier being formed to provide an arcuate series of spaced detents therein equidistant from the center of rotation of said carrier, and a spring latch carried by the other of said carrier and upright for selective locking engagement with a selected one of said detents to hold said carrier in an adjusted position.
